UNITED STATES PATENT OFFICE.

BARNAD BRIODY, OF DETROIT, MICHIGAN.

SAFETY APPLIANCE FOR RAILWAY-SWITCHES.

SPECIFICATION forming part of Letters Patent No. 307,909, dated November 11, 1884.

Application filed March 28, 1884. (No model.)

To all whom it may concern:

Be it known that I, BARNAD BRIODY, of Detroit, county of Wayne, State of Michigan, have invented a new and useful Improvement 5 in Safety Appliances for Railway-Switches; and I declare the following to be a full, clear, and exact description of the same, such as will enable others skilled in the art to which it pertains to make and use it, reference being had to the accompanying drawings, which form a part of this specification.

My invention consists of the combinations of devices and appliances hereinafter specified, and more particularly pointed out in the 15 claims.

In the drawings, Figure 1 represents a plan view illustrating my improved device with the switch closed, so as to leave the main line unbroken; Fig. 2, a similar view with the 20 switch open, so as to throw the train upon the side track. Fig. 3 is a side elevation representing an elevated pointed rail. Fig. 4 is a side elevation of an elevated rail, showing how its ends are bent down. Fig. 5 is a cross- 25 section through Fig. 2.

It is well known that one of the greatest sources of railway accidents arises from open switches, whereby a train under speed is unexpectedly shifted off onto the side track, and 30 so caused to collide with cars upon the side track.

It is the object of my invention to overcome 35 the liability of such an accident, and to provide a mechanism which, should the switch be left open, would immediately shift the cars back onto the main track without danger to either lives or property.

In carrying out my invention, A and A' represent the main track, B and B' the side 40 tracks, C any switch.

D is a rail. Its end d is depressed to a point slightly below the level of the flanges of the car-wheels. The tread of the rail then gradually rises until it is at or slightly above 45 the level of the adjacent rail B. It reaches this level at or about the point d', so that the flange of the wheel riding upon this rail would at this point easily ride off onto the adjacent rail B.

E is what I term an "elevated rail and point." 50 The point e of this rail is at the level of the top of the adjacent rail B', and is slightly

notched into the rail at this point, so that the wheel will readily run from the rail B' onto the point. After passing beyond the point 55 the rail gradually rises until its tread is sufficiently high to elevate the flange of the car-wheel above the level of the adjacent rail A'; and this elevated portion of the rail extends from the point e' to the point e².

F is a guard-rail securely fastened at f to the rail B, and from this point inclining toward the adjacent rail A, so as at this point to direct the adjacent wheel onto the main track A.

The operation of the device will now be understood. If the switch is closed, as in Fig. 1, the track is clear and the train passes freely; if, however, through carelessness, the switch is left open, as shown in Fig. 2, it is 70 apparent that the train when it reaches the switch will be deflected to the side track, B and B'; but immediately after passing onto the side track the car-wheel flanges will ride up onto the rail D until the flanges are on a 75 level with the top of the adjacent rail B. At this instant the opposite wheels will ride up on the pointed rail E, which will lift the flanges above the level of the adjacent rail A', and will at the same time crowd the wheels over 80 toward the main track, so that the flanges on the opposite side of the car will ride off from the rail D onto the tread of the adjacent rail B.

Now, it will be observed that the rails B and B' are constantly diverging from the main 85 track A A' while the pointed rail E and the rail B are approaching each other. It is therefore seen that as the wheels advance the rail E will first crowd the flanges of the opposite wheels off from the rail D until they ride on the tread 90 of the rail B, and a little farther on the flanges will ride off from the rail B and cause the wheel to drop down between the rails A and B. A little later the guard-rail F will shift the wheels onto the rails of the main track A 95 and A', and so the train which started onto the side track is deflected quickly onto the main track.

It will be observed that thus far no means have been described by which the train could 100 be shifted onto the side track. This feature I will now proceed to describe.

G is an equalizing-bar pivoted at g. The opposite ends are connected, respectively, with

the rails D and E, and their motion is controlled by a lever, H, so that by lifting or actuating the lever the rails D and E are simultaneously moved toward each other, so as to be free from the adjacent rails B and B', and as long as they are in this position a train may pass freely onto the side track. This is indicated by dotted lines in Fig. 2. Now, in order that, through carelessness, these rails D and E may not be thus shifted out of place, I prefer that they shall be forced back into place by a spring as soon as the switchman's hand is removed from the lever H. This may be accomplished in any convenient manner by the proper location of a spring; but, as a matter of convenience, I prefer to employ the natural spring of the pointed rail E, that rail being held rigidly at its farther extremity, and be sprung away from the rail by the action of the lever H. I would have it understood that I do not limit myself to any particular spring mechanism, so also the rails might be thrown back into place by the action of a weight on the lever H, this weight being always sufficient to shift the rails back into place whenever the switchman ceases to lift upon the lever. This construction avoids all liability to accident by reason of an open switch, for should the switchman simply throw the switch C and fail to lift the lever H the train would first pass off onto the side track and be then shifted back onto the main track, as before explained, while to throw it upon the side track it is only necessary for the switchman, after throwing the switch C, to step to the lever H and lift upon that lever until the train has passed entirely upon the side track.

The rails A and B, within the limits of this appliance, are preferably located so close together that as the flange rides off from the rail B the tread of the wheel projects sufficiently far to ride onto the adjacent rail A without permitting the wheel to drop down between the two rails. If, however, for any reason, this relation of the rails A and B cannot be maintained, I would in that event build up between the tracks A and B, so that the flange in riding off from the rail B would ride

onto this filling, which would hold the tread of the wheel sufficiently elevated to run freely onto the track A when shifted by the rail F.

What I claim is—

1. A safety appliance for switches, consisting of the combination, with the main and side tracks, of rails D and E, substantially as and for the purposes described. 55

2. The combination, with the main and side tracks, of a rail, D, adapted to receive the flanges of the wheels and lift them to the level of the side track, and a rail, E, adapted to receive the tread of the wheels and elevate them so as to permit the flanges to ride over onto the main track, substantially as described. 60

3. The combination, with the main and side tracks, of the rails D and E, and means for simultaneously bringing their extremities toward each other and away from the side track, substantially as described. 65

4. The combination, with the main and side tracks, of rails D and E, a lever for simultaneously forcing the two rails away from the side track, and mechanism for automatically returning them to place, substantially as described. 70

5. The combination, with the main and side tracks, of rails D and E, automatically operating to move in one direction, and a lever for simultaneously shifting them away from the side track, substantially as described. 75

6. In combination with the main and side tracks, the rails D and E, and a lever for simultaneously shifting them away from the side track, the rail E serving as a spring to force the rails back into position when the lever is released, substantially as described. 80

7. The combination, with the main and side tracks, of rails D and E and a guard-rail, F, substantially as and for the purposes described.

In testimony whereof I sign this specification in the presence of two witnesses. 90

BARNAD BRIODY.
